US00D759118S

(12) United States Design Patent
Kim et al.

(10) Patent No.: US D759,118 S
(45) Date of Patent: * Jun. 14, 2016

(54) DISPLAY SCREEN OR PORTION THEREOF
WITH ICON

(71) Applicant: Samsung Electronics Co., Ltd.,
Suwon-si (KR)

(72) Inventors: Na-Young Kim, Seongnam-si (KR);
Yoon-Jeong Kim, Seoul (KR); Jiu Seo,
Bucheon-si (KR); Jae-Han Lee,
Suwon-si (KR)

(73) Assignee: Samsung Electronics Co., Ltd.,
Suwon-si (KR)

() Term: 14 Years

(21) Appl. No.: 29/486,308

(22) Filed: Mar. 28, 2014

(30) Foreign Application Priority Data

Nov. 8, 2013 (KR) 30-2013-0056359

(51) LOC (10) Cl. 14-04

(52) U.S. Cl.

USPC D14/495

(58) Field of Classification Search

USPC D14/485-495; D18/26, 31, 32, 33

CPC G06F 3/04817

See application file for complete search history.

(57) CLAIM

We claim the ornamental design for a display screen or portion thereof with icon, as shown and described.

DESCRIPTION

FIG. 1 is a front view of a display screen or portion thereof with icon showing our new design; and,

FIG. 2 is a front view of a second embodiment thereof.

The long dash, short dash broken lines shown in FIGS. 1 and 2 represent the display screen or portion thereof and form no part of the claimed design.

1 Claim, 2 Drawing Sheets
